UNITED STATES PATENT OFFICE.

STEFAN KISS-ECSEGI, OF VIENNA, AUSTRIA.

MANUFACTURE OF UNWELDED CHAINS.

Application filed April 4, 1924, Serial No. 704,222, and in Austria April 5, 1923.

The several methods have been proposed in the past to manufacture unwelded chains, the links of which consist of two eyes or annuli, which stand at right angles to each other. In a number of these processes the links are formed of bar-shaped blanks, the ends of which are formed into eyes, which eyes are brought together by bending the middle part of the bar-shaped blank, forming one eye which stands at right angles on the eye which was produced by the bending of the middle part of the bar-shaped blank. As it is necessary that the eyes of the chain-links thus produced, fit with as little clearance as possible onto the blank of the following link, which was hooked into the preceding link, it resulted, that at least one of the eyes of the introduced link could not be completely finished, since the finished half of the eye of the link could not be introduced through the opening of the eye of the finished preceding link. In order to eliminate this difficulty, the annular half-eyes were formed on the blank after the blank had been passed through the preceding link. This process was carried out by applying already known methods, consisting of pressing and stamping, which however necessitated high pressure and a number of complicated operations. It was also proposed to form the annular eye-halves on the blank, prior to its being passed through the preceding link and then to change the shape of the eye by pressing it sideways into a shape, which would permit its passing through the finished eye of the preceding link, whereafter the shape is changed again into an annular half-eye. These heretofore applied manufacturing methods required high pressures, a number of complicated operations (up-setting, stamping, punching, removal of the bur, etc.). An additional disadvantage was that the compressing of the eye-halves and their reopening represented a serious abuse of the material which necessarily reduced the strength of the material.

The manufacturing process which forms part of the present invention permits the using of a comparatively small force in forming the eye-halves at the ends of a bar-shaped blank, further a very simple method of finishing the eye without any waste of material, all without an abuse of the material, thus obviating the danger of weakening the strength of the material.

With chains of comparatively small size, this method can be carried out without heating the blank, at least for the greater part of the operations required. In addition the simplicity of this process permits the use of mechanical equipment of very simple design.

This manufacturing method is explained below and illustrated in the enclosed drawings, which show the various manufacturing stages of the blank.

Figs. 1 and 2 show in side view and end view, respectively, the shape of the blank which enters into the operation; Figs. 3 and 4 show in side view and cross section, respectively, the shape of the blank after the end portion has been split and the middle portion curved; Figs. 5 and 6 similarly show the blank after straightening the halves of the split end portions; Figs. 7, 8 and 9 show in side view, cross section and plan view, the shape of the blank after the split end portions have been bent into U-shape. Figs. 10 and 11 show in side view and cross section the shape of the blank after the two halves of the end portions have been opened to half eyes, the blank having been passed through the eye of a finished link. Figs. 12 and 13 show the manner in which the blank is bent together to form a link; and Figs. 14, 15 and 16 show a plurality of blanks formed from a long rod and stages in the manufacture thereof, corresponding to Figs. 1, 3 and 5, respectively.

The blank according to Figs. 1 and 2 is a round rod, the ends of which are frustoconical in shape. Such a rod may be produced by cutting or other known methods. This blank is split near its ends in its axes over a certain length, without splitting the end parts *a* (Fig. 3). This splitting can be performed with different methods, the best of which is to change the relative position of the two parts *b* and *c* in the splitting-plane, this being accomplished by a shearing action, as shown in Fig. 4 in cross-section. The parts of the blank, which are to be split, are held in two jaws, which can be moved relatively towards each other. It is of course sufficient to move one jaw only and to keep the other stationary, thus causing by shearing action the severing of the two halves.

Simultaneously with this operation it is possible to give the middle part *d* of the blank a light curving in the splitting-plane

with the purpose to prevent the turning of the blank, by holding this curved part in a proper tool for the purpose of carrying out the splitting operation. After this operation has been carried out, the two halves *b* and *c* are straightened out again, presenting the picture, which is shown in Figs. 5 and 6, in contradistinction to the appearance as shown in Fig. 4. There results a small deformation of the cross-section of the blank, which however has no bearing upon the final product, since it is only a preparatory step in the whole process.

The blank is now brought into the shape shown in Fig. 7; i. e. the split ends of the blank are brought into the shape of an **U** and the curve of the middle part *d* is increased. This bending operation causes, as shown in Fig. 8 in cross-section and in Fig. 9 in plane-view a slight opening of the split halves *b* and *c*, which is quite desirable, as it is helpful in the further manufacturing steps to be taken.

When in this shape, the blank can be passed through the eye *e* of a finished link (Figs. 10 and 11). The two halves of this split are now opened, as shown in Fig. 11 in dotted lines until they form one plane, thus producing an annular shape. The opening-up of the two split halves *b* and *c* can be accomplished by a mandrel-shaped tool, this being followed by a stamping tool, which presses the annular halves into a die, at the same time upsetting these halves in order to obtain the desired annular form. In this pressing operation the material of the ends *a* of the original blank, which were not split, and the material *f* between the curved part *d* and the split halves *b* and *c* is forced into the material of the annular ring, by preventing the lateral deflection of the material by proper means, thus causing a compression of the material in those parts, where the danger of splitting of the material is to be feared. The material of the connecting part *f* also is used to form the required connection between the finished half-eyes *g* and the middle part *d*.

The next step is the bending of the middle part *d* as seen in Fig. 12 and the pressing together of the half-eyes *g* until they lie closely against each other. This is simply done by applying pressure exerted onto the two eye-halves *g* in the direction of the longitudinal axis of the blank. With this operation the link of the chain is finished, and Fig. 13 shows three links of such a finished chain. The process is continued by inserting another blank of the shape, shown in Fig. 7, through the last preceding link of the chain, after having passed through the stages, shown in Figs. 1, 3 and 5, whereafter the operations shown in Figs. 11 and 12 are repeated, etc.

This splitting of the rod-shaped blank, as

shown in Figs. 3 and 4, requires, as will easily be understood, simple tools and a small amount of power. The producing of the shape, as shown in Fig. 7 does not present any difficulties, and finally it does not require complicated tools or great power, in order to produce out of the preceding operation the final shape *g*, as shown in Fig. 10, since the transplantation of material is very small. As the stamping is done in closed dies, there is no necessity for an additional operation for the removal of the bur.

It goes without saying that the method described above can be altered in various respects. For instance the splitting of the ends of the blank could also be performed after the stage, shown in Fig. 7, this e. g. by sawing. In this stage of the process of manufacture, the splitting could also be produced by a relative motion of the two halves, by using the proper tools. One also could perform the operations illustrated in Figs. 3, 5 and 7 after having inserted the blank in the preceding link of a chain, or else, one could perform the operations resulting in the stages, shown in Figs. 3 and 5 on the blank, prior to its inserting into the preceding chain-link, and the operation, resulting in producing the shape shown in Fig. 7, after inserting the blank in the preceding chain-link. One also could take a long rod comprising blank portions *h* separated by notches *i* and, without severing the notched parts *i* from one another (see Fig. 14), produce the shapes shown in Figs. 3 and 5 on this long rod (see Figs. 15 and 16), thereafter severing the notched parts *i* from one another. These operations could be performed, for example, by a simple rolling process.

In order to carry out the various steps in the manufacturing process, properly equipped machine-tools, as e. g. presses or hammers could be used. The stamping of the eye-halves is performed through the pushing forward of a mandrel-shaped tool into a closed die, without producing a bur.

What I claim as my invention and desire to secure by Letters Patent is:

1. A process for manufacturing links of unwelded chains, consisting in splitting a blank bar at spaced portions by shifting the two parts of the blank to be separated in opposite directions within the splitting plane, thereby producing a shearing action, enlarging the resulting splits, bringing the parts containing these splits into the shape of half-eyes and bending the blank so as to combine the two half-eyes to one eye to which is connected a second eye standing at a right angle to the combined one and being produced by bending the blank between said spaced portions.

2. A process for manufacturing links of unwelded chains consisting in splitting a

- blank bar at spaced portions, bending the split parts into the shape of a U, opening the split parts, bringing them into the shape of half-eyes and bending the blank so as to combine the two half-eyes to one eye to which is connected a second eye standing at a right angle to the combined one and being produced by bending the blank between said spaced portions.
10. 3. A process for manufacturing links of unwelded chains consisting in splitting a blank bar at spaced portions by shifting the two parts of the blank to be separated in opposite directions within the splitting plane, producing, thereby a shearing action, straightening out the split parts again bending these parts into the shape of a U, opening the split parts, bringing them into the shape of half-eyes and bending the blank so as to combine the two half-eyes to one eye to which is connected a second eye standing at a right angle to the combined one and being produced by bending the blank between said spaced portions.
15. 4. A process for manufacturing links of unwelded chains consisting in splitting a blank bar at spaced portions, giving the intermediate part a slight curving, enlarging the resulting splits, bringing the parts containing these splits into the shape of half-eyes and bending the blank so as to combine the two half-eyes to one eye to which is connected a second eye standing at a right angle to the combined one and being produced by bending the blank between said spaced portions.
20. 5. A process for manufacturing links of unwelded chains consisting in splitting a blank bar at spaced portions, bending the intermediate part of the blank into a nearly semi-circular shape, enlarging the resulting splits, bringing the parts containing these splits into the shape of half-eyes, the not-split parts of said spaced portions and the material of the middle part of the blank adjacent to the split part being upset and forced into the material of the half-eyes and bending the blank so as to combine the two half-eyes into one eye to which is connected a second eye standing at a right angle to the combined one and being produced by the tendency of the blank between said spaced portions.
25. 6. A process for manufacturing links of unwelded chains consisting in splitting a blank bar at spaced portions, giving the intermediate part a slight curving in the splitting plane, bending the split parts into the shape of a U, bending the intermediate part of the blank into nearly semi-circular shape, opening the split parts, bringing them into the shape of half-eyes, the not-split parts of the spaced portions of the blank into a nearly semi-circular shape, and the material of the intermediate part of the blank adjacent to the split parts being upset and forced into the material of the half-eyes and bending the blank so as to combine the two half-eyes into one eye to which is connected a second eye standing at a right angle to the combined one and being produced by bending the blank between said spaced portions.
30. 7. A process for manufacturing links of unwelded chains consisting in splitting a blank bar at spaced portions, the parts of the spaced portions not to be split being cone shaped, giving the intermediate part a slight curving in the splitting plane, bending the split parts into the shape of a U, bending the intermediate part of the blank into a nearly semi-circular shape, opening the split parts, bringing them into the shape of half-eyes, the not-split parts and the material of the middle part of the blank adjacent to the split parts being upset and forced into the material of the half-eyes and bending the blank so as to combine the two half-eyes into one eye to which is connected a second eye standing at a right angle to the combined one and being produced by bending the blank between said spaced portions.
35. 8. A process for manufacturing unwelded chains composed of links produced as set forth in claim 1, the blanks being passed through the eye of the last finished chain-link before the split portions of the blank are enlarged.
40. 9. A process for manufacturing unwelded chains composed of links produced as set forth in claim 2, the blanks being passed through the eye of the last finished chain-link before the split portions of the blank are enlarged.
45. 10. A process for manufacturing unwelded chains composed of links produced as set forth in claim 3, the blanks being passed through the eye of the last finished chain-link before the split portions of the blank are enlarged.
50. 11. A process for manufacturing unwelded chains composed of links produced as set forth in claim 4, the blanks being passed through the eye of the last finished chain-link before the split portions of the blank are enlarged.
55. 12. A process for manufacturing unwelded chains composed of links produced as set forth in claim 5, the blanks being passed through the eye of the last finished chain-link before the split portions of the blank are enlarged.
60. 13. A process for manufacturing unwelded chains composed of links produced as set forth in claim 6, the blanks being passed through the eye of the last finished chain-link before the split portions of the blank are enlarged.
65. 14. A process for manufacturing unweld-

ed chains composed of links produced as set forth in claim 7, the blanks being passed through the eye of the last finished chain-link before the split portions of the blank are enlarged.

15. A weldless non-separable chain composed of a plurality of links, each link having a pair of eyes integral with and in planes at right angles to each other, one of

said eyes being composed of a pair of split 10 similar portions, a cross section of either portion being substantially a semi circle and the outward center part of each of said portions being of dense compressed metal.

In testimony whereof I have signed my name to this specification.

STEFAN KISS-ECSEGI.

ed chains composed of links produced as set forth in claim 7, the blanks being passed through the eye of the last finished chain-link before the split portions of the blank 5 are enlarged.

15. A weldless non-separable chain composed of a plurality of links, each link having a pair of eyes integral with and in planes at right angles to each other, one of

said eyes being composed of a pair of split 10 similar portions, a cross section of either portion being substantially a semi circle and the outward center part of each of said portions being of dense compressed metal.

In testimony whereof I have signed my name to this specification.

15 STEFAN KISS-ECSEGI.

Certificate of Correction.

It is hereby certified that in Letters Patent No. 1,605,593, granted November 2, 1926, upon the application of Stefan Kiss-Ecsegi, of Vienna, Austria, for an improvement in "The Manufacture of Unwelded Chains," errors appear in the printed specification requiring correction as follows: Page 3, line 52, claim 5, for the word "tendency" read *bending*; same page, lines 63 and 64, claim 6, strike out the words and comma "of the blank into a nearly semi-circular shape,"; and that the said Letters Patent should be read with these corrections therein that the same may conform to the record of the case in the Patent Office.

Signed and sealed this 21st day of December, A. D. 1926.

[SEAL.]

M. J. MOORE,
Acting Commissioner of Patents.
